(57) **CLAIM**

I claim the ornamental design for a motorcycle air cleaner housing, as shown and described.

DESCRIPTION

FIG. 1 is a perspective view of a preferred embodiment of the invention showing the top, front, and first side thereof.

FIG. 2 is a perspective view of the preferred embodiment of the invention showing the bottom, front, and second side thereof.

FIG. 3 is a perspective view of the preferred embodiment of the invention showing the top, front, and second side thereof.

FIG. 4 is a front elevation view of the preferred embodiment of the invention.

FIG. 5 is top plan view of the preferred embodiment of the invention.

FIG. 6 is bottom plan view of the preferred embodiment of the invention.

FIG. 7 is an elevation view of the first side of the preferred embodiment of the invention; and,

FIG. 8 is an elevation view of the second side of the preferred embodiment of the invention.

Broken lines shown in the drawings are environment and do not form part of the claimed design.
